UNITED STATES PATENT OFFICE.

FRANK A. FALK, OF STACYVILLE, IOWA.

LATCHING DEVICE.

Application filed December 10, 1925. Serial No. 74,506.

This invention relates to a latching device for use in connection with the hinged sections of the engine hood or bonnet of a motor vehicle, and has for its object to provide a device of such class, in a manner as hereinafter set forth, with means arranged interiorly of and operated from the exterior of a hinged section of the engine hood or bonnet for detachably latching such section in closed position.

Further objects of the invention are to provide a latching device, of the class referred to, in a manner as hereinafter set forth, which is simple in its construction and arrangement, strong, durable, having its latching and releasing elements concealed, reducing the rattling of the hood or bonnet section to a minimum when it is latched in position, thoroughly efficient and convenient in its use, having its latching members and the releasing means for these latter protected by the hood section, readily installed with respect to the engine hood or bonnet, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a side elevation of an engine hood showing the adaptation therewith of a latching device therefor, in accordance with this invention, and with the elements of the device arranged inwardly with respect to the hood section illustrated in dotted lines.

Figure 2 is a fragmentary view, in elevation, of an engine hood looking towards the inner face of one of the hinged sections of the hood and illustrating the latching members and the releasing means therefor, and with the hinged section of the hood latched.

Figure 3 is a view similar to Figure 2 with the hinged section of the hood released.

Figure 4 is a section on line 4—4, Figure 1.

Figure 5 is a section on line 5—5, Figure 1.

Figure 6 is a section on line 6—6, Figure 5.

Referring to the drawings in detail, the engine hood or bonnet of the motor vehicle is indicated generally by the reference character 1, the radiator at 2, and one of the side bars of the chassis at 3. As is well known, the engine hood or bonnet of a motor vehicle is set up with two hinged sections, one at each side thereof, so that access can be had to the engine when the section is swung outwardly, and each section is provided, exteriorly thereof, with means for detachably securing the section in closed position. The drawings illustrate the adaptation of a latching device, in accordance with this invention, with but one hinged section of the engine hood, but it is to be understood that a latching device is to be employed with each of the hinged sections of the hood. The hinged section illustrated is indicated at 4, and is hinged as at 5. The radiator 2 as well as the inner end of the hood 1 is rabbeted, as at 6, to provide seats for the ends of the hinged section, as well as providing means whereby the outer face of the hinged section will be flush with the inner end of the hood 1 and outer face of the radiator 2.

Mounted on the side bar 3 of the chassis is an inverted T-shaped member formed of a centrally disposed, vertically extending leg 7 and a pair of oppositely extending legs 8, 9, disposed at right angles with respect to the lower end of the lug 7. The leg 9 terminates in a depending lip 10, which abuts against the rear edge of the side bar 3. The inverted T-shaped member provides what may be termed a "combined guide and anchoring element." The leg 8 projects outwardly from the leg 7 and the leg 9 extends inwardly from the leg 7. The lower terminal portion 11 of a front wheel fender 12 is interposed between the leg 8 and the bar 3. The leg 9 is secured to the side bar 3 by hold-fast devices 13, and interposed between said leg 9 and the bar 3 are spacing members 14 through which extend the hold-fast devices 13. The leg 9, in proximity to each end thereof, is upset to provide its lower face with an annular groove 15, and the wall of the latter is formed with an opening 16. The function of the grooves 15 will be presently referred to. The leg 7 provides a guide for the lower portion of the section 4, as well as an

abutment to prevent the lower portion of the section 4 from swinging inwardly when such section is latched, and furthermore said leg 7 acts as a closure between the lower end 5 of the section 4 and the leg 8 when the section 4 is in latched position.

A pair of latching members is employed and each of which consists of a resilient body portion 17 and a hook 18 extended 10 from the upper end of the body portion 17 and projecting forwardly at an inclination. The body portion 17 is formed from a coiled spring of substantial length and has its lower coil extended through the opening 16 15 and seated in the groove 15 formed in the lower face of the leg 9 and by this arrangement the latching member is anchored in position. Each latching member is arranged in close proximity to the leg 7.

20 Carried by the inner face of the section 4, near the bottom thereof, is a shiftable holding element coacting with the latching members for maintaining the section 4 in latched position. The holding element consists of a 25 shaft 20, provided in proximity to each end thereof with a crank 21 engageable with a latching member for the purpose of latching the section 4 in closed position. The shaft 21, centrally thereof, is provided with 30 a crank 22 connected with a shifting element to be presently referred to for the shaft 20. Secured to the inner face of the section 4, near the bottom thereof, are pairs of spaced barrels 23, which provide 35 bearings for the shaft 20.

The shifting element for the shaft 20 consists of an upstanding rod, referred to generally by the reference character 24 having the major portion of its length bent to extend 40 at opposite inclinations, as at 25, 26, and with the inclined portion 26 connected, as at 27, to the crank 22. The inclined portion 26 is of greater length than the portion 25 and is arranged below the latter, and said 45 portion 25 merges into a right angularly disposed portion 28 which pivots in and is connected, as at 29, to the outer end of a crank arm 30.

The section 4, forwardly of its transverse 50 median and below its longitudinal median is formed with an opening 31, through which extends an operating shaft 32. Secured to the inner face of the section 4, below the opening 31, by the hold-fast devices 55 33 is an upstanding offset arm 34, which provides a bearing as well as a support, for the inner end of the shaft 32. To prevent the outward movement of the shaft 32, it has its inner end provided with a stop pin 35, which abuts against the rear face 60 of the arm 34. The crank arm 30 is keyed to the shaft 32 so that when the latter is turned the crank arm 30 will be carried therewith. Mounted on the shaft 32 and interposed between the crank arm 30 and sec-

tion 4 is a spacing member 36. The shaft 32 projects forwardly from the section 4, and is provided with a stop disk 37 exteriorly of the section 4, and carried by and extended from the disk 37 is a handle member 38.

The crank arm 30 not only provides means for actuating the shifting element for the shaft 20, but further provides means when it is shifted to the position shown in Figure 2 to lock the holding element in its position of latching engagement with respect to the latching members. When the crank arm 30 is shifted to the position shown in Figure 2 to lock the holding element, the handle member 38 is in lowered position as shown in full lines in Figure 1. When it is desired to unlatch the section 4, the handle member 38 is moved to the dotted line position shown in Figure 3 and which shifts the eccentric 30 to the full line position shown in Figure 3, causing thereby the shaft 20 to rock in a direction so that the cranks 21 will be shifted downwardly and away from the hooks 18, as shown in Figure 5 and the section 4 can then be swung outwardly to the dotted line position shown in Figure 5 and the section elevated. When latching the section 4, the latter is swung to full line position, shown in Figure 5, the handle member 30 is then shifted to full line position shown in Figure 1, which rocks the shaft 20 in the opposite direction and provides for the cranks 21 to engage with the hooks 18, and which are held in such position by the locking action of the crank arm 30, whereby the section 4 is detachably latched in position.

It is thought the many advantages of a latching device for the hinged sections of an engine hood or bonnet, in accordance with this invention, can be readily understood, and although the preferred embodiment of the invention is as illustrated and described, yet it is to be understood that changes in the details of construction can be had which will fall within the scope of the invention as claimed.

What I claim is:—

1. A latching device for the hinged sections of the engine hood of a motor vehicle comprising a pair of latching members adapted to be connected with the chassis of the vehicle and positioned interiorly with respect to the hood section, a holding element adapted to be carried by the inner face of the hood section and coacting with said members for latching the section in closed position, a shifting element for said holding element, a crank arm arranged interiorly of the hood section for operating said shifting element to move said holding element to and from holding position and further for locking said holding element in engagement with said members, means operated exterior-

ly of the hood section and connected with the crank arm for operating the same, and said holding element consisting of a rock shaft provided with a pair of cranks coacting with said members for latching the hood section in closed position.

2. A latching device for the hinged sections of the engine hood of a motor vehicle comprising a pair of spaced latching members adapted to be connected with the chassis of the vehicle and positioned interiorly with respect to the hood section, a pivoted holding element adapted to be carried by the inner face of the hood section, common to and coacting simultaneously with said members for latching the section in closed position, a shifting element for said holding element, a crank arm arranged interiorly of the hood section for operating said shifting element to move said holding element to and from holding position and further for locking said holding element in engagement with said members, means operated exteriorly of the hood section and connected interiorly of the latter crank arm for operating the same, and each of said latching members consisting of a resilient body portion provided with a hook coacting with the holding element to maintain the hood section in closed position.

3. A latching device for the hinged sections of an engine hood comprising a pair of spaced resilient latching members positioned interiorly with respect to the hinged section of the hood, a combined guide and anchoring element adapted to be secured with the chassis of the vehicle, said element common to and provided with means for anchoring the lower ends of said members and further with means to constitute an abutment for and arranged inwardly of the lower portion of the hood section, a holding element adapted to be carried by the hood section, interiorly thereof, said holding element common to and coacting simultaneously with said members for latching the hood section, means positioned interiorly of and supported from the hood section for operating the holding element to and from holding position and further for locking the same in holding position, and means operated exteriorly of the hood section and provided with an inwardly extending shaft connected with said first mentioned means for operating the same.

4. A latching device for the hinged sections of an engine hood comprising a pair of spaced resilient latching members positioned interiorly with respect to the hinged section of the hood, a combined guide and anchoring element adapted to be secured with the chassis of the vehicle, said element common to and provided with means for anchoring the lower ends of said members and further with means to constitute an abutment for and arranged inwardly of the lower portion of the hood section, a holding element adapted to be carried by the hood section, interiorly thereof, said holding element common to and coacting simultaneously with said members for latching the hood section, means positioned interiorly of and supported from the hood section for operating the holding element to and from holding position and further for locking the same in holding position, means operated exteriorly of the hood section and provided with an inwardly extending shaft connected with said first mentioned means for operating the same, and said holding element consisting of a rock shaft provided with a pair of cranks coacting with said latching members.

5. A latching device for the hinged section of a motor vehicle engine hood comprising a pair of spaced latching members including means for anchoring them to the chassis of the vehicle inwardly with respect to the hood section, a holding element pivotally connected to the inner face of the hood section, common to said members and including means to simultaneously coact with said members for latching the hood section in closed position forwardly of said members, an upstanding shiftable element of angular contour connected at its lower end to the holding element for shifting it on its pivot in opposite directions, means arranged interiorly of the hood section and having its outer end connected to the upper end of the shiftable element for actuating it to operate the holding element, and pivotally mounted means extending through the hood section, operated from the exterior thereof and having its inner end connected to the inner end of the actuating means for the shiftable element for operating said actuating means.

In testimony whereof, I affix my signature hereto.

FRANK A. FALK.
